UNITED STATES PATENT OFFICE.

LOUIS B. HASBROUCK, OF ELMIRA, NEW YORK.

SPINNING FRAME.

Application filed November 16, 1923. Serial No. 675,035.

This invention relates to improvements in spinning frames and the like, and aims to eliminate the waste of spinning fiber and the injury to the machinery of the frame resulting from breakage of rovings during spinning.

The invention is directed particularly to the elimination of such waste and such damage in worsted spinning frames, where the loss caused by the breakage of rovings is large owing to the high value of worsted rovings. Owing to the length of the fiber of worsted rovings, which cannot be drawn apart like cotton rovings, and to the adjustment of the drawing rolls necessary in a worsted frame, it has heretofore been thought impossible to provide such frames with automatic means for severing a broken roving in advance of the drawing rolls. As a result, the efficiency of worsted spinning frames has heretofore been impaired by the losses caused by the "balling up" of broken rovings in the drawing rolls.

In accordance with the present invention a worsted spinning frame is provided with severing apparatus adjustable with the front drawing rolls and adapted to cut a worsted roving, and with automatic balanced actuating mechanism connected with the severing apparatus, engaging the rovings beyond the drawing rolls, and so arranged that it is not thrown out of balance by a change in the position of the drawing rolls and the severing apparatus.

While the invention is thus of special value when incorporated in a worsted spinning frame, its use is by no means limited to such spinning frames, and many features of the invention, particularly those contributing to the ruggedness of the device and its delicacy of operation, may advantageously be incorporated in many other types of spinning frames including cotton spinning frames.

A feature of the invention consists in combining the severing apparatus and the actuating mechanism in a stop-motion device or attachment which may be applied to existing worsted spinning frames without alteration of any parts of the frame and without interfering in any way with the operation of the frame.

The nature of the invention may best be understood by a detailed description of a worsted spinning frame embodying it. Such a frame is shown in the accompany-

ing drawings, but, in order to illustrate more clearly the novel parts of the apparatus, many of the known parts of the worsted frame have been omitted in the drawings.

Fig. 1 is a face view, looking in the direction of the arrow 1 in Fig. 2, of the rolls and roll supports of a worsted spinning frame, showing a stop motion device with each of its units in running position;

Fig. 2 is a transverse section on the line 2—2 of Fig. 1;

Fig. 3 is a fragmentary transverse section on the line 2—2 of Fig. 1 with one of the actuating shafts removed;

Fig. 4 is an enlarged fragmentary side view of the outer thread guide of one of the units of the stop-motion device;

Fig. 5 is a face view of a pair of units of the stop-motion device, both in running position;

Fig. 6 is an outer end view, looking in the direction of the arrows 6 in Figs. 2 and 5, showing the outer portion of a pair of actuating shafts of the stop-motion device;

Fig. 7 is an inner end view, looking in the direction of the arrow 7 in Fig. 5, of a pair of units of the stop-motion device, showing the severing apparatus and the resetting and locking mechanism;

Fig. 8 is a transverse section on the line 8—8 of Fig. 7;

Fig. 9 is a fragmentary section on the line 8—8 of Fig. 7 showing the individual lock of a pair of the units in raised position;

Fig. 10 is an enlarged face view of the rear portion of a pair of units, showing one of them in running position and the other in severing position;

Fig. 11 is a perspective view of the thread guide which forms part of the severing apparatus;

Fig. 12 is a transverse section on the line 12—12 of Fig. 10, showing the locking and resetting mechanism of a pair of units;

Fig. 13 is a perspective view of the plate of the locking mechanism; and

Fig. 14 (on Sheet 2) is a transverse section on the line 14—14 of Fig. 10, showing one of the supports for the sliding bar of the locking mechanism.

The spinning frame.—The framework of the worsted frame shown in the drawings includes a creel board A, a side beam B, inclined cross-beams C extending between

the creel board and the side beam at suitable intervals and each having at its lower end an enlarged support D which is secured to the side beam B, and longitudinal rails 5 E extending between the supports D and having their ends secured thereto. Fig. 1 shows only the portion of the frame between two of the cross-beams C. It is to be understood that the frame is much longer than 10 the distance between two of these cross-beams and that a large number of cross-beams are provided.

The lower rolls F of the outer set of rolls are mounted on a longitudinal shaft G supported in bearings provided in the supports D. The upper rolls F' of the outer set are mounted in pairs on stub shafts H whose ends are supported on brackets J secured to the longitudinal rail E and whose 15 middles are held down by spring clamps K secured to curved arms L which extend from the rail E and are usually formed integral therewith.

The other drawing rolls are mounted on 20 carriages adjustable along the cross-beams C which contain longitudinal slots M in which the carriages are secured. The inner drawing rolls N, N' are mounted on carriages P which are formed to provide a 25 slideway Q for a reciprocating rod R which extends the entire length of the spinning frame to carry guides which direct the rovings to the inner set of drawing rolls, N, N'. The intermediate sets of rolls S, S' and T, 30 T' are mounted on adjustable carriages U and V.

In the operation of the frame rovings are drawn from supply bobbins W mounted on the creel board A, through thread guides 35 mounted on the rod R, and between the four sets of rolls in a direction approximately parallel to the cross-beams C on which the roll carriages may be adjusted. They are then spun and wound on bobbins carried by 40 spindles located in front of the side beam B. One such spindle X with its bobbin Y is shown in Fig. 2. Between the outer set of rolls F, F' and caps Z which guide the yarns spun from the rovings to the bobbins each 45 roving passes through a thread guide located in line with the axis of the spindle on which the thread spun from that roving is wound. Although the character of the rovings is, of course, changed during their 50 passage through the drawing rolls, the term "roving" is for convenience herein applied to them until such time as they are actually 55 spun into yarn or thread and wound on the bobbin.

60 The parts of the spinning frame thus far described are in common use and do not in themselves constitute a part of my invention.

65 The stop-motion device.—The frame illustrated is provided with a stop-motion de-

vice consisting of a plurality of units, there being one unit for each roving which is drawn from a supply bobbin to a spindle. For convenience in supporting their working parts, the units are arranged in pairs. 70 Each unit includes severing apparatus 15 or 15' located in front of the inner set of rolls N, N', and actuating mechanism therefor having the form of a shaft 16 or 16' extending under all the rolls. The stop motion device includes, also, thread guides 17 mounted on the reciprocating rod R and differing in form from the guides ordinarily carried by this rod, and thread guides 18 mounted at the outer ends of the actuating shafts 16 or 16' and replacing the thread guides ordinarily provided between the outer set of rolls and the spindles. 75

The fixed supporting parts.—The fixed parts of the stop-motion device provide a support for the severing apparatus 15, 15' and supporting bearings for the actuating shafts 16, 16'. The fixed parts include 80 brackets 20 and bars 21 and 22.

One bracket 20 is provided for each pair 85 of units. Each bracket 20 has a tab 25 which is secured by means of a screw 26 to the rail E at the base of one of the arms L, and a flat cross-piece 27 containing two 90 holes through which a pair of the actuating shafts 16 and 16' are passed.

The bar 21 is mounted on carriages 95 30 which are secured in the slots M of the cross-beams C. The bar 21 is parallel to the axes of the rolls and may extend the entire length of the frame. To it are secured 100 depending plates 31, each containing two holes 32, 32' providing bearings for the upper ends of a pair of the actuating shafts 16, 16'. The bar 21 also supports the resetting and locking mechanism which is hereinafter described.

The bars 22, which bear the severing apparatus 15 and 15' of each pair of units, 105 extend between the carriages P which bear the inner set of rolls N, N' so that these bars are always located immediately in front of this set of rolls regardless of the adjustment of the roll carriages on the cross-beams C. Each bar 22 has a slotted end which is attached by means of a screw 33 to a bracket 34 fixed on one of the carriages P. This provides for a longitudinal adjustment of 110 each bar 22. In the form illustrated each bar 22 is located between the reciprocating rod R and the front rolls.

The actuating mechanism.—The actuating shafts 16, 16' of a pair of units are so positioned by the holes in the cross-piece 27 of the bracket 20 and the holes 32, 32' in the plate 31, in which these shafts are mounted, that their axes are parallel to the cross-beams C and substantially parallel to the path of the roving through the drawing rolls. To prevent the shafts 16, 16' from 115 120 125 130

slipping downwardly and outwardly, each shaft is provided with a thrust bearing 35, including a collar 36 adjustably secured to the shaft by means of a set screw 37, and a set of bearing balls 38 between this collar and the cross-piece 27 of the bracket 20.

The shafts 16, 16' are free to turn in their bearings, but their turning movements are limited by pins 40, 40' mounted on discs 41, 41' fixed on the shafts 16 and 16', respectively, and projecting through arc-shaped slots 42, 42' in the plate 31. To facilitate the operation of the resetting mechanism which is hereinafter described, the slot 42 is placed below the hole 32 while the slot 42' is placed above the hole 32'. When the pin 40 is at or near the inner end 43 of the slot 42, the shaft 16 is in normal or "running" position, i. e. in position to hold the corresponding severing means clear of its roving, and when this pin is moved into engagement with the outer end 44 of the slot 42 the shaft 16 is in "severing position", i. e. in position to cause the corresponding severing means to cut its roving. The shaft 16' is in running position when the pin 40' is at or near the outer end 44' of the slot 42', and in severing position when this pin is in engagement with the inner end 43' of this slot. It follows that the turning movement of the shaft 16 from running to severing position is in a clock-wise direction looking from the outer end of the shaft, while the turning movement of the shaft 16' from running to severing position is in an anti-clockwise direction. The angular turning is in each case less than 90°.

The turning of each shaft is controlled by a lateral projection on the shaft engaging a roving beyond the outer drawing rolls F, F', and the turning is utilized by means of a lateral projection on the shaft engaging the severing apparatus 15 or 15' to actuate this apparatus to cut the roving in advance of the inner drawing rolls N, N'. It should be noted that the length of each shaft is such that it extends, in the direction of its axis, from a point some distance in advance of the inner drawing rolls N, N' to a point beyond the outer drawing rolls F, F', so that, at the inner end of the shaft its axis is close to the corresponding severing apparatus 15 which is located in advance of the inner drawing rolls, while at its outer end, its axis is close to the portion of the roving extending from the outer drawing rolls to a spindle. In consequence both the lateral projection which engages this part of the roving and the lateral projection which engages the severing apparatus need extend only a short distance from the axis of the shaft and may easily be made strong and rigid.

The lateral projection of each shaft which engages the corresponding severing appara-

tus consists of a long crank 50 formed by offsetting the portion of the shaft between its thrust bearing 35 and the plate 31. In the running position of the shafts these cranks 50 extend upward as shown in Figs. 70 5 and 8 and at the right-hand side of Figs. 10 and 12, although not necessarily directly upward as shown in these figures; while, when any shaft is in its severing position its crank 50 is inclined inward toward the adjacent shaft as shown at the left-hand side of Figs. 10 and 12.

The lateral projection of each shaft which engages a roving beyond the outer drawing rolls is located on the portion of the shaft 80 outside its bracket 20. This portion of each shaft is offset at 51, and provided with a radial arm 52. When the shafts are in running position the offset portions 51 of the two shafts extend horizontally toward 85 each other, while the arms 52 extend horizontally away from each other. On the outer ends of the arms 52 are mounted the thread guides 18. Each thread guide 18 includes a hub 53 mounted on the 90 end of one of the arms 52, an arm 54 projecting radially from this hub, and an eye 55 at the outer end of the arm 54. When the shafts are in running position the arms 54 of the thread guides project horizontally 95 forward beyond the outer ends of the shafts, bringing the eyes 55 of the guides over two of the spindles X and in line with the axes of these spindles.

In order to provide for moving the thread 100 guides 18 out of the way when the shafts are in running position and the caps Z and the bobbins Y are to be removed from the spindles X in doffing, the hubs 53 of the guides are mounted on the arms 52 in such 105 manner that they may be turned upwardly. For this purpose the hubs 53 are mounted rotatably on the arms 52 and are secured thereto by means of pins 56 fixed in the arms 52 and passing through arcuate slots 110 57 in the hubs 53.

The offset portion 51 of each shaft is provided on its under side with a weight 58 which counterbalances the weight of the arm 52 and the thread guide 18. In addition, each arm 52 is provided with an adjustable weight 59 secured to it by means of a set screw 60. The adjustable weights 59 may be so positioned that each actuating shaft is in equilibrium when in running position. Such equilibrium is, however, unstable, since because of the weight of the crank 50, the center of gravity of the entire shaft is above its axis. It is, however, desirable so to set the adjustable weights 59 that each shaft when in running position has a slight tendency to turn inward toward its severing position and thus to raise its arm 52 and its thread guide 18 toward the position shown in dotted lines in Fig. 130

6. As soon as such turning begins, the weight of the crank 50 tends to continue and to accelerate it. Each shaft is, however, so nearly balanced when in running position, that a very slight pressure exerted by a roving passed through the eye 55 of the thread guide 18 serves to prevent the shaft from turning, as long as the roving is intact. When, however, a roving breaks in or beyond the drawing rolls and its pressure on the eye 55 is released, the shaft 16 or 16' associated with the roving immediately turns inwardly to its severing position.

This inward turning of a shaft 16 or 16' on the breaking of its roving is utilized to actuate the severing apparatus 15 or 15' to cut this roving in advance of the inner drawing rolls.

The severing apparatus.—The severing apparatus 15 or 15' of each unit includes turnably mounted severing means 65 or 65', and a fixed thread guide 70 or 70', adapted to retain a roving in position to be cut by the severing means.

25 The thread guides 70 and 70' are alike, except that they are turned in opposite directions. The form of a thread guide 70 is best shown in the perspective view, Fig. 11. Each guide is box-shaped, having two 30 transverse flanges 71, 72 and a longitudinal strap 73 connecting them. The front or inner flange 71 contains an eye 74 and a lateral passage 75 through which the roving may be drawn into this eye. A guard 76 prevents the roving from slipping out of the eye 74. The outer or rear transverse flange 72 contains an upwardly-opening recess 77 into which the roving may be dropped. A supporting flange 78 extends 35 outwardly from the lower end of the rear transverse flange 72 and is attached to the top of the bar 22 by means of a screw 79, as best seen in Fig. 10.

40 Since each thread guide 70 extends over the reciprocating rod R, the thread guides which are ordinarily mounted on the rod R are replaced by special thread guides 17 which are formed so as not to interfere with the thread guides 70. Each thread guide 45 17 is provided with an attachment plate 80 which is secured to the reciprocating rod R by means of a screw 81 (see Figs. 7, 8 and 10). The end portions of the attachment plate 80 are turned over to provide flanges 50 82 resting on the top of the rod R. A tongue 83 extends from the upper edge of the central portion of the attachment plate 80, passes under the bar 22 and then upwardly 55 behind the thread guide 70. The upwardly extending portion 84 of the tongue 83 contains a recess 85 for the roving and provides a pair of ears 86 for guiding the roving into this recess.

60 When the frame is threaded, each roving 65 is passed first through one of the thread

guides 70 and then through one of the thread guides 17 before it is entered between the drawing rolls. It follows that although the path of a roving through the drawing rolls is constantly varied by the reciprocation of the thread guide 17 through which it passes, and although its path between its supply bobbin W and its thread guide 70 is varied by the position on the bobbin from which the roving is being drawn, it is nevertheless true that the path of each roving through its thread guide 70 remains always the same, being in a straight line from the eye 74 to the bottom of the recess 77. It is in this unchanging part of its path that each roving may be cut by one of the turnable severing means 65 or 65'.

A common support 90 for the turnable severing means 65 and 65' of each pair of units is secured to the bar 22. Each support 90 has an upper flange 91 extending over the bar 22 and secured to it by means of a screw 92, a depending flange 93, and a lower flange 94. The upper and lower flanges 91 and 94 contain two sets of aligned 90 holes which form bearings for the turnable severing means 65 and 65'. Each severing means includes a shaft 95 and 95' mounted in these bearings, a bent arm 97 adjustably secured to the upper end of this shaft, a knife 98 at the outer end of this arm, and a crank arm 99 extending from the lower end of this shaft and provided with means for engaging the crank 50 of one of these actuating shafts 16 or 16'.

The shafts 95, 95' are provided with thrust bearings 96 engaging the flange 91. Each of these shafts extends at right angles to the corresponding actuating shaft 16 or 16' and is spaced outwardly from its 105 actuating shaft.

Each knife 98 has two blades 100 similar to the ordinary safety razor blades and having their sharpened edges 101 crossed to provide a V-shaped slot 102.

The crank arm 99 of each severing means 65 or 65' extends in a direction substantially opposite to that in which the arm 97 of this severing means extends. The engaging means 105 of each crank arm is adapted to engage 115 the crank 50 of one of the shafts 16 or 16' at any point along the length of this crank, so as to transfer a turning movement of this actuating shaft to the corresponding shaft 95 or 95' of the severing means. Each 120 engaging means 105 has the form of a long U-shaped hook having sides 107, 108 embracing one of the cranks 50. Each hook 105 has sufficient depth so that its bottom 109 does not interfere with the downward 125 component of the movement of the crank 50 which occurs when one of the actuating shafts 16 or 16' turns from its running to its severing position. Such downward component of the movement of the crank 50 130

does not of itself cause any movement of the crank arm 99, but the lateral or inward component of the movement of a crank 50 which occurs when its actuating shaft turns from 5 running to severing position brings the crank 50 into engagement with the side 107 of the hook 105, swinging the crank arm 99 inwardly to the position shown at the left in Fig. 10. The turning thus imparted to the shaft 10 95 or 95' swings the arm 97 of this shaft outwardly. Conversely, when one of the actuating shafts 16, 16' is moved from its severing position to its running position by the resetting means hereinafter described, 15 the crank 50 of this shaft engages the side member 108 of one of the hooks 105, swinging the crank arm 99 outwardly and the knife bearing arm 97 inwardly. As may be best seen in Fig. 10, the hook 105 is approximately 20 perpendicular to the crank 50 when the crank is turned in, and is inclined to this crank when the crank is turned up in running position. The sides 107 and 108 of the hook are, therefore, separated by a distance 25 sufficient to enable them to embrace the crank 50 when the hook is inclined to the crank, as shown at the right side of Fig. 10.

The arm 97 of each severing means may be so adjusted on its shaft 95 or 95' that the 30 center of gravity of each severing means 65 or 65' is above the axis of its shaft 95 or 95' when the corresponding actuating shaft 16 or 16' is in running position. It is not essential that the center of gravity be directly 35 above the axis, but it is desirable that it should be nearly so. It follows that when one of the actuating shafts is in running position and is, as has been said, approximately in a position of unstable equilibrium, 40 the corresponding severing means 65 or 65' is in a position of unstable equilibrium, or nearly so. Thus, when the parts are in running position, each serving means is balanced so that it exerts no appreciable force 45 on the corresponding actuating shaft and so does not increase the pressure of the thread guide 18 of its actuating shaft against a roving. It follows that the only pressure upon the rovings when the parts are in running 50 position is that caused by the very slight tendency of the actuating shafts to turn out of their running position, and this pressure is so little that it does not cause any increased tension or strain on the rovings. 55 When, however, a roving breaks in or beyond the drawing rolls, and one of the actuating shafts 16 or 16' starts to turn inwardly, the corresponding severing means 65 or 65' is immediately moved out of a position 60 of equilibrium so that the weight of its arm 97 and knife 98 assists the turning of the actuating shaft in swinging the knife outwardly.

When a roving breaks, the outward swing 65 of the knife 98 cooperating with this roving

continues until the arm 97 on which this knife is mounted comes into contact with the rear transverse flange 72 of one of the thread guides 70 or 70', as shown in full lines at the left-hand side of Fig. 10. When a 70 knife reaches this position, the sharpened edges 101 of its blades 100 lie in the path of the roving which is passing through the thread guide 70 or 70', and the blades 100 are inclined to the roving with their inner or 75 front surfaces at an obtuse angle thereto. Consequently, the travel of the roving under the pull of the drawing rolls draws it into the V-shaped slot 102 and against the sharpened edges 101 so that it is cut by them. 80

It should be noted that each severing means may be operated to cut a roving by the application of a very slight force. Three features contribute to this result. In the first place, each severing means is normally 85 in a position of unstable equilibrium. Secondly, the final movement of each knife which brings its sharpened edges into contact with a roving has a component in the direction of travel of the roving, so that the 90 travel of the roving tends to assist, and not to oppose, the final movement of the knife into severing position. And finally, the relative movement of the roving and the sharpened edges which causes the actual cutting 95 of the roving is caused by the travel of the roving and necessitates no movement of the knife.

The resetting and locking mechanism.— 100 When an individual roving is to be rethreaded after it has broken, and has been cut, it is desirable that the unit associated with this roving be reset and locked in running position until the threading has been completed. Furthermore, when the bobbins are 105 ready for doffing, it is desirable to lock all the units in running position. A feature of the invention consists in providing both individual and common resetting and locking means for the units. 110

An individual resetting and locking means is provided for each pair of units. It consists of a bar 111 slidably mounted on the plate 31 of the pair of units and having side arms 112, 112' cooperating with segmental recesses 113, 113' in the discs 41, 41'. The arms 112 of the slide bar 111 engage the outer side of the plate 31, and the slide bar has an overturned lower end running in a vertical recess 119 in the lower part of the plate, and tabs 114 engaging the inner side of the plate. The slide bar 111 may be raised or depressed by means of a handle 115. It is retained against accidental movement by a spring 116 secured to the inner side of 115 the plate 31 by means of a screw 117.

The segmental recesses 113, 113' in the discs 41, 41' are so positioned that when an actuating shaft is in a severing position, the upper end 118 of its recess rests on one 130

of the side arms 112 or 112' of the bar 111, as shown at the left-hand side of Fig. 12. In order to reset a unit from severing into running position, the bar 111 is raised by means 5 of the handle 115 so that the side arm 112 or 112' of the bar which is in engagement with the disc of a unit in severing position turns the actuating shaft of this unit outwardly into running position. If one of the 10 shafts of the pair is already in running position, the raising of the slide bar does not change its position, but serves merely to lock it in running position. After a broken roving has been rethreaded, the slide bar 111 15 cooperating with this unit is depressed so as to leave the actuating shaft of the unit free to turn into severing position in case the roving breaks.

The means for simultaneously resetting 20 and locking all the units in running position comprises a slide bar 120 running the whole length of the spinning frame. This bar is slidably mounted in brackets 121 which are secured to the bar 21 by means of screws 25 122. The slide bar 120 is provided with recesses 123 formed in its lower side and embracing the rear ends of the actuating shafts 16, and recesses 123' formed in its upper edge and embracing the rear ends of the actuating shafts 16'. The recesses 123, 123' 30 are of sufficient width to permit a limited longitudinal movement of the slide bar 120 without bringing the sides of the recesses into contact with the actuating shafts 16 or 16'.

In order to lock all the units in running position and at the same time to reset into running position any unit which may be in severing position, the slide bar 120 is moved 40 in the direction of the arrow 124 to bring it into the position shown in Fig. 7. This brings the sides 125 of the recesses 123 into contact with the pins 40, and the sides 125' of the recesses 123' into contact with the pins 40', so as to hold the pins 40 against the inner ends 43 of the slots 42 in the plates 31, and the pins 40' against the outer ends 44' of the slots 42', thus retaining all the actuating shafts in running position. After 45 doffing, the slide bar 120 is moved in a direction opposite to that of the arrow 124, so that its recesses 123, 123' lie behind the slots 42, 42' of the plates 31, leaving each actuating shaft free to turn into its severing 50 position in the case of the breaking of a roving.

From the above description it is apparent 60 that the invention provides a very sensitive automatic mechanism for cutting in advance of the drawing rolls any roving which may break. As a result, the loss of spinning material which has heretofore resulted from the 65 breaking of rovings in worsted spinning frames is entirely eliminated. At the same time labor costs are reduced, as the frames

do not require an operator constantly in attendance to watch for broken rovings.

The severing means with its sharp-edged blades cuts a worsted roving notwithstanding the strength and length of the fibers of 70 such rovings. The mounting of the actuating mechanism on an axis parallel to the direction in which the drawing rolls are adjusted results in producing a device which is not thrown out of balance by the necessary 75 adjustment of the drawing rolls in the worsted frame. The specific device which has been described is, therefore, particularly adapted to worsted spinning and is, I believe, 80 the first device capable of eliminating waste in worsted spinning.

My invention is, however, by no means limited to its use in connection with worsted spinning, as many features of the invention are of importance in connection with 85 the spinning of cotton and other rovings. Among these features are the ruggedness of the actuating mechanism obtained by giving it the form of a long turnable shaft extending across all the drawing rolls and having 90 comparatively short lateral projections to engage a roving beyond the drawing rolls and to engage the severing apparatus in advance of the drawing rolls; and the delicacy 95 of operation obtained by the balancing of the severing means which relieves the actuating mechanism of all strains in its normal position and thus makes it possible to adjust the actuating mechanism to exert so slight a side pressure on a roving that no increased tension or strain on the roving is caused thereby.

Furthermore, it should be understood that the invention is not limited to the particular form and arrangement of the parts of 105 the specific device which has been described, except in so far as may be specified in the claims which follow. In the claims the expression "severing means" or "severing mechanism" is to be understood to include any 110 means for severing the roving including clamping it so that it is torn apart as well as actually cutting it as is done in the specific device described.

What I claim is:

1. In a spinning frame, the combination of a thread guide providing eyes engaging a roving at two spaced points between the supply bobbins and the reciprocating guides in advance of the inner rolls, a sharp-edged knife, and means operative on the breaking of said roving in or beyond the drawing rolls to cause relative movement between said thread guide and the knife to bring the edge of the knife into a straight line joining the 120 eyes of the thread guide.
2. In a spinning frame, the combination of means for guiding a roving through two fixed points, a sharp-edged knife, and means operative on the breaking of said roving in 125 130

or beyond the drawing rolls to move said knife to bring its edge into the path of the roving between said points.

3. In a spinning frame, the combination of means for guiding a roving through two fixed points, a knife having a sharp-edged blade, a mounting permitting movement of said knife between a normal position in which its blade is spaced from the roving and a severing position in which the edge of its blade is between said points and the front surface of its blade is at an obtuse angle to the roving, and means operative on the breaking of said roving in or beyond the drawing rolls to move said knife from its normal to its severing position.

4. In a spinning frame, the combination of means engaging a roving at two spaced points, a knife having two sharp edges forming a V-shaped severing slot, and a mounting for the knife permitting movement thereof between a normal position in which it is spaced from said roving and a severing position in which its edges are adjacent to said roving and so inclined to the roving that the travel of the roving draws the roving into the V-shaped slot to be cut by the edges.

5. A severing knife as claimed in claim 4, in which the V-shaped severing slot is formed by the sharpened edges of two thin overlapping blades.

6. In a spinning frame, the combination of a knife having a sharp edge, a mounting for said knife permitting movement thereof from a normal position in which its edge is spaced from a roving to a severing position in which its edge is in contact with said roving and so arranged that the final movement of the knife into its severing position has a component in the direction of travel of the roving, and means operative on the breaking of said roving in or beyond the drawing rolls to move said knife from its normal toward its severing position.

45 7. The combination with a spinning frame having adjustably mounted drawing rolls, of severing means adjustably mounted so that it may always be located just in advance of the inner drawing rolls, and substantially balanced actuating means engaging a roving beyond the drawing rolls and adapted, on the breaking of said roving, to actuate the severing means in any location thereof.

55 8. The combination with a spinning frame having adjustably mounted drawing rolls, of severing means adjustable with the inner drawing rolls, substantially balanced actuating means therefor turnably mounted on an axis parallel to the direction in which the drawing rolls are adjustable and engaging a roving beyond the drawing rolls, and cooperating parts secured to said severing means and said actuating means respectively and adapted to remain in engagement with

each other in all locations of the severing means.

9. The combination with a spinning frame having adjustably mounted drawing rolls, of severing means adjustable with the inner drawing rolls, an engaging part on said severing means, and an actuating shaft mounted with its axis parallel to the direction in which the drawing rolls are adjustable, an arm on said shaft engaging a roving beyond the drawing rolls, and a crank on said shaft adapted to engage the engaging part of the severing means in all locations of the severing means.

10. The combination with a spinning frame, of turnable means for severing a roving in advance of the drawing rolls, and a movable member so engaging the severing means as to prevent movement thereof in either direction out of a position of unstable equilibrium so long as said roving is intact and adapted to move said severing means out of equilibrium when said roving breaks.

11. The combination with a spinning frame, of turnable means for severing a roving in advance of the drawing rolls, a turnable actuating member therefor normally held nearly in a position of unstable equilibrium by engagement with said roving beyond the drawing rolls, and a connection between the actuating member and the severing means arranged to set the severing means substantially in a position of unstable equilibrium when the actuating member is in its normal position, so that, while the severing means exerts no force on the actuating member when the latter is in its normal position, it tends to assist the movement of the actuating member as soon as the latter is displaced from its normal position.

12. In a spinning machine and in combination with the drawing rolls thereof, an actuating shaft extending under the drawing rolls, means at the outer end of said shaft engaging a roving, a second shaft extending in advance of the inner drawing rolls and at an angle to the actuating shaft, means on said second shaft for severing a roving in advance of the drawing rolls, and cooperative engaging means on said shafts arranged to cause a turning of the second shaft on a turning of the actuating shaft.

13. In a stop-motion device for a spinning frame, the combination of two shafts extending at an angle to each other and each mounted for limited turning movement, a crank on one of said shafts, a crank arm on the other of said shafts, and a hook on said crank arm surrounding said crank.

14. The combination with a spinning frame having adjustably mounted drawing rolls, of a severing device mounted for adjustment with the inner drawing rolls and including a shaft, a crank arm on said shaft,

and a hook on said crank arm, a substantially balanced actuating shaft extending under all the drawing rolls and parallel to the direction of adjustment of the drawing rolls, and a crank on the actuating shaft adapted to extend through said hook in all locations of the severing means.

15. The combination with a spinning frame, of means for severing a roving in advance of the drawing rolls, and mechanism for actuating said severing means on the breaking of said roving in or beyond the drawing rolls, comprising a turnably mounted shaft extending from the severing means to a point beyond the drawing rolls, a lateral projection near one end of said shaft engaging the roving beyond the drawing rolls, and a lateral projection near the other end of the shaft engaging the severing means.

16. In a spinning frame, actuating mechanism for a roving-severing apparatus, comprising a turnably mounted shaft extending across the drawing rolls in the direction approximately parallel to the path of a roving through the rolls, and lateral projections spaced longitudinally on said shaft, one positioned to engage the roving beyond the drawing rolls, and the other positioned to engage a severing apparatus in advance of the drawing rolls.

17. In a spinning frame, actuating mechanism for a roving-severing apparatus, comprising a turnably mounted shaft, means for limiting the turning of the shaft in each direction, a crank on the shaft which extends upward when the shaft is turned to its extreme position in one direction, a radial arm on the shaft which extends horizontally when the shaft is turned to its extreme position in said direction and is inclined upwardly when the shaft is turned to its extreme position in the other direction, a roving-engaging element on said arm, and a counterweight on said shaft slightly overbalancing the weight of said arm and said element.

18. In a spinning frame, actuating mechanism for a roving-severing apparatus, comprising an inclined turnably mounted shaft extending under the drawing rolls, a radial arm on said shaft beyond the drawing rolls, and a roving-engaging arm extending horizontally outward from the free end of the first arm when the first arm is in a horizontal position.

19. The combination with a spinning frame, of a pair of turnable severing means mounted between two of the rovings in advance of the inner rolls and each having a severing arm, a pair of actuating means mounted between said two rovings, each weighted so that it tends to turn inwardly and each having an outwardly extending arm engaging one of said rovings beyond

the drawing rolls to restrain it from turning inwardly while said roving is intact, and a connection between each actuating means and one of said severing means arranged to swing its severing arm outward against one of said rovings when the actuating means associated with said roving turns inwardly.

20. In combination with a spinning frame, a pair of shafts mounted between two of the rovings in advance of the drawing rolls, a severing arm extending from each of said shafts, a pair of actuating shafts extending under the drawing rolls between said two rovings, a weight on each of said shafts tending to cause it to turn inwardly, an arm on each of said shafts extending outwardly therefrom and engaging one of said rovings beyond the drawing rolls to prevent the shaft from turning inwardly while said roving is intact, and a connection between each of said actuating shafts and one of said first-mentioned shafts arranged to turn said shaft to swing its severing arm outward against one of said rovings when the actuating shaft associated with said roving turns inwardly.

21. In a spinning frame, the combination of a plurality of severing means positioned to sever the rovings in advance of the drawing rolls, a plurality of turnably mounted actuating shafts connected to said severing means respectively, each shaft having a projection engaging a roving beyond the drawing rolls and being eccentrically weighted so that it tends to turn into position to actuate its severing means on the breaking of said roving in or beyond the drawing rolls, individual locking means for restraining any one of said shafts against such turning, and collective locking means for restraining all such shafts against such turning.

22. In combination with a spinning frame, a plurality of pairs of severing means mounted between pairs of the rovings in advance of the drawing rolls, a plurality of pairs of actuating shafts extending under the drawing rolls between pairs of the rovings, a weight on each of said shafts tending to turn it inwardly, an arm on each of said shafts extending outwardly therefrom and engaging one of the rovings beyond the drawing rolls to prevent the shaft from turning inwardly while said roving is intact, a connection between each of said actuating shafts and one of said severing means arranged to swing it outwardly against one of said rovings when the one of the actuating shafts associated with said roving turns inwardly, individual locking means for restraining any pair of shafts against inward turning, and collective locking means for restraining all the shafts against each turning.

23. Actuating mechanism for a stop-motion device, comprising a plurality of shafts mounted side by side and eccentrically weighted so that certain of them tend to 5 turn in one direction and others in the other direction, means for limiting the turning of each shaft in each direction, an eccentric pin mounted on each shaft, those on the shafts tending to turn in one direction being above 10 the axes of the shafts and those on the shafts tending to turn in the other direction being below the axes of the shafts, and a slide bar having transverse engaging means which, in one position of the bar, engage all said pins 15 and lock each shaft against turning, and, in another position of the bar, leave each shaft free to turn under the influence of its eccentric weight.
24. Actuating mechanism for a stop motion device, comprising a plurality of eccentrically weighted shafts mounted side by side, a disc fixed on each of said shafts, a fixed plate adjacent to the disc of each shaft and containing an arc shaped slot, a pin in 20 each disc extending into the slot in one of said plates so as to limit the turning movement of its shaft in each direction, a weight on each shaft tending to cause turning thereof, and a side bar extending across the 25 shafts and containing recesses which in one position of the bar are located opposite the slots in the plates and in another position of the bar are located so as to engage the pins and retain them against movement in 30 the slots.
25. Actuating mechanism for a stop motion device, comprising a plurality of pairs of shafts mounted side by side and eccentrically weighted so that the shafts of each 35 pair tend to turn inwardly toward each other, a disc fixed on each shaft, a fixed plate adjacent to the discs of each pair of shafts and containing an arc-shaped slot above the axes of the shafts and an arc-shaped slot below the axes of the shafts, a pin fixed in the disc of one shaft of each pair and extending into the one of the upper arc-shaped slots, a pin fixed in the disc of the other shaft of each pair and extending 40 into one of the lower slots, a vertically slidable member mounted on each plate and having arms adapted to engage the pins of a pair of shafts and move such pins upwardly to the upper ends of their slots, a slide 45 bar extending across all these shafts and having in its upper edge recesses located to lie opposite the upper slots in all the plates and in its lower edge recesses located to lie 50 opposite the lower slots in all the plates.
26. The combination with a worsted spinning frame having a side rail, slotted cross-beams, and drawing rolls mounted on carriages adjustable on said cross-beams, of a 55 bar extending between the carriages on which the inner rolls are mounted, roving- 60 severing apparatus mounted on said bar, a second bar extending between the cross-beams in advance of the roll carriages, brackets secured to the side rail of the frame, and actuating shafts for said severing apparatus extending between said second bar and said brackets. 70
27. The combination with a spinning frame having drawing rolls and a reciprocating rod in advance of the inner drawing 75 rolls, of a fixed bar extending between the inner drawing rolls and the reciprocating rod, fixed thread guides mounted on said bar and extending over the reciprocating rod, reciprocating thread guides secured to 80 said reciprocating rod and extending under said fixed bar and up behind said fixed guides, and means for severing a roving within any of said fixed guides. 85
28. In a stop motion device for spinning frames, severing apparatus comprising a knife having two sharp edges forming a V-shaped slot having an angle large enough to avoid gripping a roving in the corner of the slot, and means for positioning the knife 90 with its edges adjacent to a roving and so inclined to the roving that the travel of the roving draws it into the V-shaped slot to be cut by the edges. 95
29. The combination with a spinning frame having adjustably mounted drawing rolls, of severing means adjustably mounted so that it may always be located just in advance of the inner drawing rolls, and actuating means engaging the roving beyond the 100 drawing rolls and adapted, on the breaking of said roving, to actuate the severing means in any location thereof. 105
30. The combination with a spinning frame having adjustably mounted drawing rolls, of severing means adjustable with the inner drawing rolls, actuating means turnably mounted on an axis parallel to the direction in which the drawing rolls are adjustable and engaging a roving beyond the 110 drawing rolls, and cooperating parts secured to said severing means and said actuating means respectively and adapted to remain in engagement with each other in all locations of the severing means. 115
31. In a stop motion for spinning frames, the combination with turnable severing means and a turnable actuator therefor, of a connection between the severing means and the actuator preventing independent movement thereof and arranged to set one of these parts substantially in a position of unstable equilibrium when the other of these parts is placed substantially in the position 120 of unstable equilibrium. 125
32. The combination with a spinning frame, of means for severing a roving in advance of the drawing rolls and mechanism for actuating said severing means on the breaking of said roving in or beyond the 130

5 drawing rolls, comprising a turnably mounted shaft extending from the severing means to a point beyond the drawing rolls, a thread guide mounted on said shaft near its outer end and positioned to direct the roving from the drawing rolls to a spindle, and a projection near the other end of said shaft engaging the severing means.

10 33. The combination with a spinning frame, of means for severing a roving in advance of the drawing rolls, and mechanism for actuating said severing means on the breaking of said roving in or beyond the drawing rolls, comprising an eccentrically weighted turnable shaft extending from the severing means to a point beyond the drawing rolls, a normally horizontal projection near one end of said shaft engaging the roving beyond the drawing rolls, and a projection near the other end of the shaft engaging the severing means.

15 34. In a spinning frame, actuating mechanism for a roving-severing apparatus, comprising a turnably mounted shaft extending across the drawing rolls in the direction approximately parallel to the path of a roving through the rolls, and projections spaced longitudinally on said shaft, one positioned to engage the roving beyond the drawing rolls and to guide it directly to a spindle, and the other positioned to engage a severing apparatus in advance of the drawing rolls.

20 35. In a spinning frame, actuating mechanism for a roving-severing apparatus, comprising a turnably mounted shaft extending across the drawing rolls in a direction approximately parallel to the path of a roving through the rolls and at one side of said path, and projections spaced longitudinally on said shaft, one positioned to engage the roving beyond the drawing rolls, and the other positioned to engage a severing apparatus in advance of the drawing rolls.

25 36. In a spinning frame, actuating mechanism for a roving-severing apparatus, comprising a turnably mounted shaft extending across the drawing rolls in the direction approximately parallel to the path of a roving through the rolls, and projections spaced longitudinally on said shaft, one engaging the roving beyond the drawing rolls and the other positioned to engage a severing apparatus in advance of the drawing rolls, and the shaft being eccentrically weighted so that it tends to turn in a direction to raise said first projection.

30 37. In a spinning frame, actuating mechanism for a roving-severing apparatus, comprising an inclined turnably mounted shaft extending under the drawing rolls, a normally horizontal arm on said shaft beyond the drawing rolls, and a roving-engaging element on said arm.

35 38. In a spinning frame, actuating mecha-

nism for a roving-severing apparatus, comprising an inclined turnably mounted shaft extending under the drawing rolls at one side of a path of a roving through the rolls, and a thread guide on said shaft positioned to direct the roving from the drawing rolls directly to a spindle.

40 39. In a spinning frame, actuating mechanism for a roving-severing apparatus, comprising an inclined turnably mounted shaft extending under the drawing rolls, a normally horizontal radial arm on said shaft beyond the drawing rolls, and a roving-engaging arm extending horizontally outward from the free end of the first arm and adapted to be tipped upwardly to permit doffing the spindles.

45 40. The combination with a spinning frame of a pair of actuating members mounted between two of the rovings, each weighted so that it tends to turn inwardly and each having an outwardly extending arm engaging one of said rovings beyond the drawing rolls, and means for severing each of said rovings in advance of the drawing rolls when the actuating means associated with that roving turns inwardly.

50 41. The combination with the spinning frame of a pair of turnable severing means mounted between two of the rovings in advance of the inner rolls and each having a severing arm adapted to swing outwardly against one of the rovings, and means for operating each of said severing arms when the roving with which it is associated is broken.

55 42. In combination with a spinning frame, a pair of actuating shafts extending under the drawing rolls between two of the rovings, each shaft being weighted so that it tends to turn inwardly, an arm on each of said shafts extending outwardly therefrom and engaging one of said rovings beyond the drawing rolls to prevent the shaft from turning inwardly while said roving is intact, and means for severing either of said rovings when the shaft associated with it turns inwardly.

60 43. In a spinning frame, the combination with a plurality of stop motion units each adapted to sever a roving in advance of the drawing rolls on the breaking of said roving in or beyond the drawing rolls, of an individual locking means for each unit, and collective locking means for simultaneous locking of all said units.

65 44. In a spinning frame, the combination with a plurality of stop motion units each having a severing member movable into and out of contact with a roving in advance of the drawing rolls, of an individual locking means for holding the severing member of each unit out of contact with a roving, and collective locking means for simultaneously holding all said severing members out of contact with the rovings.

45. In a spinning frame, the combination with a plurality of stop motion units each having severing means and an actuating member movable into and out of a running position in which it is in contact with a roving beyond the drawing rolls, of individual locking means for holding the actuating member of each unit in its running position, and collective locking means for simultaneously holding all the actuating members in running position.

46. Actuating mechanism for a stop motion device, comprising a plurality of shafts mounted side by side and eccentrically weighted so that alternate shafts tend to turn in one direction and the others in the other direction, means for limiting the turning of each shaft in each direction, and means for simultaneously locking all the shafts against turning under the influence of their weights.

47. Actuating mechanism for a stop motion device, comprising a plurality of turnable members mounted side by side, and resetting means adapted to engage all said members and to turn alternate shafts in one direction and the other shafts in the opposite direction.

48. Actuating mechanism for a stop motion device comprising a plurality of pairs of shafts mounted side by side and eccentrically weighted so that the shafts of each pair tend to turn inwardly toward each other, an eccentric projection on each shaft, a vertically movable slide for each pair of shafts adapted to engage the projections of said shafts and lock them against turning under the influence of their weights, and a slide movable horizontally across all the shafts adapted to engage the projection of each shaft and lock them all against turning under the influence of their weights.

49. The combination with a worsted spinning frame having a side rail, slotted cross beams and drawing rolls mounted on carriages adjustable on said cross beams, of a bar extending between the carriages on which the inner rolls are mounted, roving-severing units, one for each roving, mounted on said bar, and means for actuating each roving-severing unit on the breaking of the roving with which it is associated.

In testimony whereof I have hereunto set my hand.

LOUIS B. HASBROUCK.
